(57) **CLAIM**

The ornamental design for a tent, as shown and described.

DESCRIPTION

FIG. 1 is a front side perspective view of our tent, with the tent fly cover in place;

FIG. 2 is a rear side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a front side perspective view of our tent, with the tent fly cover removed. The claim being directed to the appearance of a combined tent and tent fly as shown in FIGS. 1-7, the tent fly being removed from the tent to show aspects of the Claim not apparent from FIGS. 1-7.

FIG. 9 is a rear side perspective view thereof;

FIG. 10 is a front elevation view thereof;

FIG. 11 is a rear elevation view thereof;

FIG. 12 is a left side elevation view thereof;

FIG. 13 is a right side elevation view thereof; and,

FIG. 14 is a top plan view thereof.

The broken lines represent portions of the design that form no part of the claim.
